APPARATUS FOR APPLYING EXTENDED SURFACE ELEMENTS TO THE TUBES OF HEAT EXCHANGE DEVICES

Martin Frisch, New York, N. Y., assignor to Foster Wheeler Corporation, New York, N. Y., a corporation of New York

Application December 20, 1938, Serial No. 246,833

10 Claims.

(Cl. 29—84)

This invention relates to heat exchange apparatus and more particularly pertains to heat exchange equipment having extended surface elements on the tubes thereof and to means for applying these elements to the tubes.

The invention provides a novel machine for applying extended surface elements to the tubes of heat exchange devices.

The nature of the invention will be understood from the following description considered in connection with the accompanying drawings, forming a part thereof, and in which:

Fig. 1 is a top plan view of a machine embodying the invention;

Fig. 2 is a side elevational view of the machine shown in Fig. 1;

Fig. 3 is an enlarged partial longitudinal sectional view of the piston head and sleeve of the machine;

Fig. 4 is a view similar to Fig. 3 but showing another position of the piston head and sleeve;

Fig. 5 is a longitudinal sectional view showing another form of piston head and sleeve, and

Fig. 6 is a transverse sectional view taken on line 6—6 of Fig. 5.

Like characters of reference refer to the same or to similar parts throughout the several views.

The embodiments of the machine selected for illustration are arranged to apply extended surface discs of aluminum or aluminum alloy of the type shown in Figs. 3 and 4, to steel tubes of U-bend form, but it will be understood that the invention is capable of general application and may be used to apply extended surface members of any form or material to any cooperating tubular member of any material.

The extended surface members shown consist of a plurality of separate discs 18 of aluminum or aluminum alloy, each of which is provided with an annular hub flange or hub 11 which extends radially outwardly from one side of the inner peripheral portion of the disc. The inner cylindrical surface of the flange 11 is of a diameter slightly less than the outer cylindrical surface of the tube 12 so that the discs must be forced onto the tubes. The outer cylindrical surface 13 of each flange 11 is inclined outwardly from the side of the disc from which the flange extends and toward the axis of the tube. Retaining rings 14, made of steel having a coefficient of expansion equal to, or somewhat less than, that of the steel tube 12, are provided with a tapering or inclined inner cylindrical surface which cooperates with the inclined surface 13 of flange 11. The diameter of the inner cylin-

drical surface of the retaining rings is preferably somewhat less than that of the surface 13 of flange 11 so that the rings may be driven onto the flanges 11 to provide a good driving fit. Desirably, the inner cylindrical portion 15 of the discs 18 and the flanges 11 may be cut or formed to provide one or more slots, not shown. Such slots provide the hub portions of the discs with a degree of resiliency they would not possess otherwise and facilitate the securing of the discs to the tubes and the maintenance of good thermal contact between the discs and tubes when the temperature of both is increased. An annular flange 16 extends outwardly from the same side of the discs from which the flange 11 extends and is spaced from the flange 11, radially outwardly thereof a distance which is sufficient so as not to interfere with the application of the retaining rings 14, and provides a shroud, or shielding means for the rings 14 to prevent exposure of these rings to the fluid on the outside of the heating elements. The flange 16 is proportioned so that its outer end portion fits snugly into an annular recess in the adjacent disc, as clearly shown in Fig. 3.

The machine for applying the extended surface elements to the tubes is supported on an H-beam 20 which is supported at its ends by H-beams 21 and 22. The form of the machine selected for illustration is arranged to apply the extended surface elements to U-bend tubular heat exchange elements having legs 23 and 24. A tube supporting device 25 receives and retains in position the U-bend portion of the tubular element, and supporting device 26 receives and retains one end of a centering bar 27, the other end of which is inserted in the end of upper leg 23, to hold in position the free ends of the tubular elements during application of the extended surface members to the lower leg 24. Supporting device 25 includes an element housing 28 having a recess therein shaped to receive the U-bend portion of the tubular element, a drift pin 29 to retain the U-bend portion in the housing 28, an element housing support 30 which may be fixed in the desired position to the H-beam 20 at one end thereof, and a latch pin 31, the inner end of which projects, under spring pressure, into one of two spaced recesses 32 in the housing 28. The supporting device 26 is fixed to H-beam 20, or it may be movable with respect to the beam 20 and have means to fix it in the desired position. Centering bar 27 is secured in position in the device 26 by means of a screw 33. The lower portion of the device 26 has an open-

ing 34 through which projects the means for forcing the extended surface discs on the tubular elements. As shown, such means comprises an hydraulic motor, the cylinder 35 of which is fixed to the right hand end portion of the H-beam 20 and the piston rod 36 of which carries a head 37 on its outer end which in turn carries a sleeve 38 thereon. Referring more particularly to Figs. 3 and 4, the piston rod head 37 has a reduced right hand end portion 39 which is threaded into the outer end of piston rod 36, and a pin 40 which passes through the rod and head retains the latter in position on the rod. The left hand end portion of the head 37 has a reduced part 41, the outer end of which engages the flange 11 of the extended surface member 10 being applied to the tube 12, and a reduced part 42 which in diameter is intermediate the diameters of part 41 and the central portion of the head. Sleeve 38 is rotatably supported on the parts 41 and 42 of head 37. The outer end of the sleeve is reduced in thickness and engages the retaining ring 14 and forces it into place after the extended surface disc 10 has been driven home. The right hand end of sleeve 38 has a plurality of spaced inclined surfaces 43 which move on corresponding surfaces on the head 37. The inclined surfaces 43 are spaced by surfaces 44 on the sleeve and head respectively which are disposed transversely to the axis of the head and sleeve. The arrangement is such that the sleeve may be rotated by hand or otherwise, so that the outer end of the sleeve will lie to the right of the outer end of head 37 as shown in Fig. 3, or will be positioned about even with the end of the head as shown in Fig. 4. A pilot 45 has a central portion of approximately the same diameter as the diameter of tube 12, a reduced portion 46 which fits tightly in the end of the tube 12, and a tapered portion 47 which extends beyond the end of tube 12 and guides the tube into the head 37 and the hollow piston rod.

The stroke of the motor which operates head 37 should be at least equal to the total overall length of the discs to be applied. The piston rod 36 is hollow and of such inside diameter that the tube 12 may enter the rod when the discs are applied. Power means other than the hydraulic motor mentioned, may be used to actuate the head 37.

The operation is as follows: A U-bend tube 12 upon which discs 10 are to be affixed, is mounted on the machine with its U-bend end in the housing 28. Draft pin 29 is then put in place and tightened up, after which centering bar 27 is put into the upper leg 23 of the element to support the upper leg, and the screw 33 is tightened to hold the bar 27 in place. Pilot 45 is next placed in the end of the lower leg 24. A disc 10 is then placed over the end of the pilot 45 and a retaining ring is placed on the end of part 41 of head 37 in the position shown in Fig. 3, the sleeve 38 first having been turned so that it is in its extreme right hand position also as shown in Fig. 3. Cylinder 35 is operated, pilot 45 enters the head 37 and the outer end of part 41 of head 37 engages the flange 11 and drives the disc 10 on the tube 12 and into its final position on the tube. During this movement, the sleeve 38 remains in its inward position on the head as shown in Fig. 3, so that the retaining ring 14 is not driven into place on the flange 11. After disc 10 has been moved into place, the piston in cylinder 35 is moved in the opposite direction a short distance, the sleeve 38 is rotated through an angle of about

90° which moves the sleeve into the position shown in Fig. 4, the piston is then moved again toward the disc 10 and the ring 14 is forced into position on the flange 11 as shown in Fig. 4. Thereafter, the piston rod and head 37 are returned to their first position, sleeve 38 is turned 90° to its first position, and the cycle is completed. Another disc is placed on pilot 45 and another retaining ring 14 is placed on part 41 of head 37, and the cycle previously described is repeated until the desired number of discs 10 has been applied to the lower leg 24 of the tubular element.

Thereafter, latch pin 31 is withdrawn from aperture 32, centering bar 27 is withdrawn from leg 23, pilot 45 is removed from the end of lower leg 24, and the tubular element with the housing 28 attached thereto, is turned 180° to bring the leg 23 in alignment with the piston head 37. The latch pin, centering bar and pilot are replaced and the machine is ready to apply discs and their retaining rings to the leg 23 in the manner previously described. When all the discs have been applied to the leg 23, the element is removed from the machine and the next element to which discs are to be applied is positioned in the machine.

Preferably, the power means to apply the discs and rings is provided with two forward speeds and pressures, one high speed at low pressure to force the discs onto the tubes and the other, a low speed at high pressure—up to the capacity of the power means—for forcing the retaining rings onto the disc flanges. However, other speeds and pressures may be employed, or the same speed and pressure may be used for both operations.

In the form of the invention shown in Figs. 5 and 6, the outer end of the hollow piston rod 36 has fixed thereto and in axial alignment therewith, an inner sleeve 50 having about the same inside diameter as the piston rod 36. An outer sleeve 51 which slides freely on the inner sleeve 50 is shorter in axial length than sleeve 50 and, as shown, is provided at its outer end with an annular flange 52 which fits over the shroud 16 of the disc 10 and engages the outwardly extending portion of the disc. The outer end of piston rod 36 and the inner end of sleeve 50 are provided with cooperating annular flanges, and the inner end of outer sleeve 51 is also provided with an annular flange. In order that the disc 10 may be driven on the tube leg 24 independently of the retaining ring 14, means are provided to cause the outer end of the sleeve 51 to project beyond the outer end of sleeve 50, so that the disc 10 may be driven on the tube leg first and to permit the outer end of sleeve 50 to project beyond the outer end of sleeve 51, so that the retaining ring 14 may be driven on the flange of the disc. In the form shown, such means comprises a split collar 53, the two cooperating parts of which are pivotally connected and have latch means, such as designated 54, to hold the two parts together. The collar has a main portion which is arranged to be disposed intermediate the inner end flanges of the sleeves 50 and 51, and, preferably, this portion has an axial length greater than the axial length of the retaining ring 14. The end portions of the collar 53 are provided with annular recesses which receive the flanges of the outer ring and the inner ring and piston rod, respectively, so as to maintain the sleeves 50 and 51 in the position shown in Fig. 5 during the time the disc 10 is being forced into place. The two parts of the split collar need not be connected

together either in the manner shown, or otherwise, that is to say, the two parts may be completely independent if desired.

The operation of the machine with this form of piston rod head is the same as that described for the form shown in Figs. 1 to 4, excepting that to force the disc 10 into place, the collar 53 is used and the outer sleeve 51 engages the disc, after which the piston head is backed up a short distance, the collar 53 is removed so as to permit the inner sleeve 50 to project beyond the end of sleeve 51 and to engage the ring 14 and drive it into position on the flange of the disc. The piston rod head is thereafter withdrawn again to allow another disc and ring to be placed in position to be applied to the tube leg, the collar 53 is put in place and the cycle is repeated until all the discs and rings are in place. A pilot, such as 45, may or may not be used with the piston rod head shown in Figs. 5 and 6.

Since changes may be made in the form, location and relative arrangement of the several parts of the apparatus disclosed without departing from the principles of the invention, it will be understood that the invention is not to be limited excepting by the scope of the appended claims.

What is claimed is:

1. Apparatus for applying extended surface elements to U-bend tubes, comprising a housing to receive and retain the U-bend end portion of one of said tubes, supporting means for said housing, means for detachably connecting the housing to the supporting means, a centering bar arranged to have one end inserted in the end of one leg of the tube, means for supporting the other end of the bar, and means operable to force the elements onto the other leg of the tube.

2. Apparatus for applying extended surface elements to U-bend tubes, comprising holding means to support and retain the U-bend end portion of one of said tubes, supporting means for the holding means, means for detachably connecting the holding means to the supporting means, a centering bar arranged to have one end inserted in the end of one leg of the tube, means for supporting the other end of the bar, and means operable to position the elements onto the other leg of the tube.

3. Apparatus for applying extended surface elements to U-bend tubes, comprising holding means to support and retain the U-bend end portion of one of said tubes, supporting means for the holding means, means for detachably connecting the holding means to the supporting means, the holding means being constructed so that it may be detachably secured to the supporting means in one of two positions each the reverse of the other, a centering bar arranged to have one end receivable in the end of either of the legs of the tube depending on the position of the holding means whereby either leg is centered by said bar and the other leg is free, means for releasably holding the other end of the bar, and means operable to position the elements onto the free leg of the tube in either position of the holding means.

4. Apparatus for applying to tubes, extended surface elements of the type having a hub flange and a retaining ring for engaging said flange to secure the element to the tube to which it is applied, comprising means for holding the tube to which the elements are to be applied, a plunger, means mounting said plunger for movement toward and from a held tube, element applying

means at the advancing end of said plunger for engaging and positioning an element, and ring applying means at the same end of said plunger so constructed as to be selectively advanced ahead of said element applying means for engaging and applying a ring.

5. Apparatus for applying to tubes, extended surface elements of the type having a hub flange and a retaining ring for engaging said flange to secure the element to the tube to which it is applied, comprising means for holding the tube to which the elements are to be applied, means including a tubular member arranged to telescope the tube and to engage and to position an element on the tube, a second tubular member carried by the first mentioned tubular member and adjustable with respect to its position thereon and arranged to engage in one position a retaining ring for the hub flange of said element, and means for retaining the second tubular member in position to engage the retaining ring.

10 6. Apparatus for applying to tubes, extended surface elements of the type having a hub flange and a retaining ring for engaging said flange to secure the element to the tube to which it is applied, comprising means for holding the tube to which the elements are to be applied, means including a tubular member arranged to telescope the tube and to engage and to position an element on the tube, a second tubular member carried by the first mentioned tubular member and adjustable with respect to its position thereon and arranged to engage in one position a retaining ring for the hub flange of said element, means for retaining the second tubular member in position to engage the retaining ring, and means for reciprocating the tubular member, the operation being such that upon movement of the tubular member in one direction the element is forced onto the tube, upon the return movement the second tubular member is adjusted to its retaining ring engaging position and upon the following movement in said one direction the ring is forced onto the flange of the element.

15 7. Apparatus for applying to tubes, extended surface elements of the type having a hub flange and a retaining ring for engaging said flange to secure the element to the tube to which it is applied, comprising means for holding the tube to which the elements are to be applied, means including a first tubular member arranged to telescope the tube, an end of said member being adapted to engage an element, means for reciprocating said tubular member, a second tubular member carried on the outer end portion of the first tubular member and having a retaining ring engaging portion and being adjustable to and from a position to engage said ring, and means for retaining the second tubular member in its ring engaging position during the ring positioning movement of the tubular member.

20 8. Apparatus for applying to tubes, extended surface elements of the type having a hub flange and a retaining ring for engaging said flange to secure the element to the tube to which it is applied, comprising means for holding the tube to which the elements are to be applied, means including a first tubular member arranged to telescope the tube, an end of said member being adapted to engage an element, means for reciprocating said tubular member, and a second tubular member carried on the outer end portion of the first tubular member and having a retaining ring engaging portion and being adjustable to and from a position to engage said ring, the

first and second tubular members having co-operable parts arranged to retain the second member in ring engaging position during the ring positioning movement of the tubular member.

9. Apparatus for applying to tubes, extended surface elements of the type having a hub flange and a retaining ring for engaging said flange to secure the element to the tube to which it is applied, comprising means for holding the tube to which the elements are to be applied, means including a first tubular member arranged to telescope the tube, an end of said member being adapted to engage a retaining ring, means for reciprocating said tubular member, a second tubular member carried on the outer end portion of the first tubular member and having an element engaging portion and being adjustable to and from a position to engage said element, and means removable from the first tubular member for retaining the second tubular member in its

element engaging position during the element positioning movement of the tubular member.

10. Apparatus for applying to tubes, extended surface elements of the type having a hub flange and a retaining ring for engaging said flange to secure the element to the tube to which it is applied, comprising means for holding the tube to which the elements are to be applied, a plunger, and means mounting the plunger for movement toward and from a held tube, the plunger having element applying means at the advancing end portion thereof adapted to engage and position an element, the plunger also having ring applying means at the advancing end portion thereof adapted to engage and apply a ring, the plunger and both said applying means being constructed and arranged so that one of said applying means may be advanced selectively ahead of the other applying means whereby elements and rings are applied alternately.

MARTIN FRISCH.
